UNITED STATES PATENT OFFICE.

GEORGE S. TENNEY, OF WALPOLE, MASSACHUSETTS, ASSIGNOR TO AMERICAN GLUE COMPANY, OF BOSTON, MASSACHUSETTS, A CORPORATION OF MASSACHUSETTS.

BUFFING-WHEEL.

No. 921,027.

Specification of Letters Patent.

Patented May 11, 1909.

Application filed June 1, 1908. Serial No. 435,932.

To all whom it may concern:

Be it known that I, GEORGE S. TENNEY, of Walpole, in the county of Norfolk and State of Massachusetts, a citizen of the United States, have invented a new and useful Improvement in Buffing-Wheels, of which the following is a specification.

A buffing wheel or drum having a detachable surface of sandpaper or the like is ordinarily made of wood or metal provided with a suitable hub by which it is mounted upon a shaft and its rim is surrounded by a tire of felt or other fibrous material. About the rim of felt is wrapped a layer of sandpaper or the like and the difficulty with devices of this character has been to attach the sandpaper in such a way that it may be quickly and easily removed and a fresh piece substituted and at the same time the sandpaper shall not overlap nor present any protuberance where the two ends meet. Various means have been devised for accomplishing this end, but the mechanism which I have shown below I believe to be the simplest and consequently the least expensive and at the same time to be the most effective for the purpose.

My invention will be understood by reference to the drawings, in which—

Figure 1 is a side elevation of a buffing wheel embodying my invention, Fig. 2 being a section on line 2—2 of Fig. 1. Fig. 3 is a sectional detail showing the construction and operation of the grippers for holding the ends of the paper, and Fig. 4 is a detail in plan of the under or inner side of the cam.

A is the wheel proper which may be of wood or metal and is provided about its rim with a cushion B of felt or the like.

C is a strip of sandpaper of a width corresponding to the width of the rim of the wheel, the strip being somewhat longer than the circumference of the wheel in order that its two ends c, c¹ may pass down between the ends of the cushion B and into the radial slot a in the wheel.

The wheel is chambered as at D, two of the walls of the chamber being parallel with the outer walls of the wheel, and two other walls being radial so that the chamber is narrower near the axis of the wheel than near its periphery. The top of the chamber is partially closed by the pieces d, d, between which is the slot a above referred to, these pieces serving as bearings for the ends of the cushion

ion B and providing an entrance into the chamber for the ends of the strip C.

E is a grip comprising jaws e each mounted on the end of an arm e¹, the arms being pivoted together at e² and held normally separated from each other by a spring e³ setting into suitable cavities e⁴ in the arms e¹. This grip lies in the chamber D and when in its opened position as shown in dotted lines in Fig. 3, its arms are separated by the spring e³ so as to afford ample space for the insertion between them of the ends, c, c¹ of the sandpaper strip C. The jaws e are provided with surfaces for engaging the sandpaper, the form of surface which now seems to me best being that shown in the drawings where the end of one of the jaws is concave, the end of the other being convex and adapted to force the ends of the strip into the concave jaw as shown in Fig. 3. This gripping operation is effected by a radial inward pull given to the grip, the arms of the grip and consequently its jaws being forced together by the narrowing up of the chamber D as it approaches the axial portion of the roll.

The wheel A is provided with a hub F which is attached thereto by means of screws or in any other suitable way, a flange f being provided for that purpose on one end of the hub. The farther end of the hub carries a cam G which sets into a suitable cavity in the wheel A and is held in place by a ring H screwed to the side of the wheel. This cam is free to be turned and on its under surface it is grooved spirally as shown at g. A pin g¹ attached to the pivot of the grip lies in the spiral groove g and as the cam is turned the spiral groove draws the grip either inward to tighten the paper or outward to loosen it as may be necessary.

The operation of the device will be easily understood. It being desirable to cover the wheel for buffing purposes, a strip of sandpaper or the like of the proper width and length, is wrapped around the wheel and the grip being open as shown in dotted lines in Fig. 3, the two ends of the strip are pushed down into the slot a, the strip being stretched as tightly as may be by hand about the rim of the wheel, the ends being bent over the edges formed by the two ends of the felt as smoothly as possible. The cam G is then turned to draw the grip inwardly toward the axis of the wheel by means of the groove g

and pin g^4 , and while so doing the side walls of the chamber D force the jaws of the grip together so that they bite upon the ends of the strip and pull the strip tight about the 5 wheel. The wheel is then in condition for use. To release the strip the cam is turned in the reverse direction which pushes the grip outward from the axis of the wheel, the spring e^3 causing the jaws to separate and 10 release the paper so that it may be easily withdrawn by hand.

The simplicity of this device is such that it would appeal to anyone skilled in the art. Comprising as it does but three parts it can 15 not easily get out of order, and moreover the working parts are so protected, being enclosed within the wheel, that they cannot be injured in any way. The radial movements are positive owing to the use of a cam 20 groove and pin by which they are caused, and the jaws acquire a firm hold on the paper by reason of the radial character of the walls of the chamber which cause the jaws to come together and acquire a firm hold on the 25 paper. There is no tendency of the parts to loosen owing to the shape of the cam groove and the relation of the cam thereto, and the arrangement as a whole allows the apparatus to perform its functions of stretching and 30 holding the paper and releasing it with the least possible manipulation.

I do not mean to limit my invention to the precise construction shown in the drawings as its details may be varied without departing 35 from the spirit thereof. The wheel shown has a concave periphery but my invention applies equally to a wheel having a convex or flat periphery.

What I claim as my invention is:

40 1. The buffing wheel above described provided with a chamber having an opening to receive the ends of a strip of abrasive paper,

a grip located within said chamber, means for giving said grip a radial movement and means for closing the jaws of said grip during 45 its inward radial movement.

2. The buffing wheel above described provided with a chamber having an opening to receive the ends of a strip of abrasive paper, a grip located within said chamber and provided with jaws, means for keeping said jaws normally open, and means for giving to said grip a radial movement, said chamber having radial walls adapted to engage said jaws and as they are drawn inwardly to close 55 them against one another.

3. The buffing wheel above described provided with a chamber having an opening to receive the ends of a strip of abrasive paper, a grip located within said chamber and provided with jaws, means for keeping said jaws normally open, and means for closing said jaws on the inward radial movement thereof, and means for moving said jaws inwardly comprising a cam pin located on said 60 grip, a cam and means whereby said cam may be operated as set forth.

4. The buffing wheel above described provided with a shaped chamber having an opening to receive the ends of a strip of abrasive paper, a grip located within said chamber and provided with jaws, means for keeping said jaws normally open, means to close said jaws upon the movement of the jaws in an inward radial direction, said wheel having 70 a central bearing, and a cam located on said central bearing and adapted to engage said grip and move it back and forth radially as described.

GEORGE S. TENNEY.
